UNITED STATES PATENT OFFICE.

PETER B. LAIRD, OF BROOKLYN, NEW YORK.

ICE-CREEPER.

SPECIFICATION forming part of Letters Patent No. 319,729, dated June 9, 1885.

Application filed February 17, 1885. (No model.)

To all whom it may concern:

Be it known that I, PETER B. LAIRD, of Brooklyn, in the county of Kings and State of New York, have invented a new and useful 5 Improvement in Ice-Creepers, of which the following is a full, clear, and exact description.

Reference is to be had to the accompanying drawings, forming a part of this specification, in 10 which similar letters of reference indicate corresponding parts in all the figures.

Figure 1 is a side elevation of one of my improved ice-creepers, shown as applied to a shoe. Fig. 2 is a bottom view of the same. Fig. 3 is 15 a sectional elevation of a part of the same, taken through the line $x x$, Fig. 2.

The object of this invention is to provide ice-creepers constructed in such a manner that they can be readily applied to and detached 20 from the soles of boots and shoes, and when attached will remain securely in place.

The invention relates to an ice-creeper constructed of two elastic wires, connected at their middle parts by a collar or band, and bent at 25 their ends to form lugs to clasp the edges of the sole and heel, and points to engage with the ice, as will be hereinafter fully described and then claimed.

A B are two elastic wires of suitable size, 30 and which are secured to each other at their middle parts by a collar or band, C. The arms

of the wires A B incline or curve from each other, and the rear arms have offsets or shoulders formed in them in such positions as to be at the front of the heel of the boot or shoe to 35 which the creeper may be attached. The ends of the arms of the wires A B are bent outward, upward, downward, inward, and then downward to form lugs D to clasp the edges of the sole and heel, and points E to take hold of the 40 ice, and thus prevent the wearer from slipping upon the said ice.

With this construction the elasticity of the wires A B allows the creepers to be readily applied to and detached from the soles of boots 45 and shoes, and holds them securely in place when applied.

Having thus described my invention, I claim as new and desire to secure by Letters Patent—

As an improved article of manufacture, an 50 ice-creeper formed of the elastic wires A B, connected at their middle portions and bent outward from said middle portions to form an X-shaped frame, the opposite ends of the wires being bent outward, upward, and downward 55 to form lugs D to clasp the edges of the heel and sole, and points E, substantially as set forth.

PETER B. LAIRD.
